WOOD-BENDING MACHINE

Karl Michaelis, Paris, France

Application November 8, 1952, Serial No. 319,587

7 Claims. (Cl. 144—254)

This application is a continuation-in-part of my co-pending application Serial No. 166,085, filed June 5, 1950 (now abandoned).

The invention to be protected in the present application relates to wood-bending machines of the type disclosed in my U. S. Patent No. 2,089,078, in which an abutment member in the form of a roll extending across the board or panel to be bent which had previously been rendered pliable, forces the wood to wrap itself around the curved surface of a former drum to which it had been secured.

In this machine, in order to make bends of different radii, the drum must be supported in exactly horizontal position in order to prevent the wood from being bent along helicoidal lines. However, the lifting of heavy equipment without changing their horizontal position requires careful and expensive machining of the glide blocks.

It is an object of the present invention to provide means for supporting, lifting and lowering the drums in a simple and inexpensive manner and for fixing them firmly at different levels.

According to this invention the drums are supported near one end of a lever pivoted on a horizontal axle which is supported by the machine bed. I prefer using a double-armed lever, whose other lever arm carries the motor serving to turn the drum. The motor acting as a counter-weight renders the adjusting of the drums easy.

The balanced lever preferably has the form of a rigid girder, for instance of the box type. In order to avoid torsional stresses acting on the lever, it may be useful to provide a pair of such levers for the support of the drum and the motor.

I further provide means for firmly connecting the free end of the drum axle, after it has been brought into position, with the machine bed.

Means should also be provided for changing the position of the abutment member relative to the point at which the work is fixed to the drum. Obviously, in bending a thick board or panel, the abutment member should be applied to the work at a greater distance from the curved drum surface, than in the case of a thinner panel.

In the drawings affixed to this specification and forming part thereof, an embodiment of the invention is illustrated diagrammatically by way of example.

In the drawings

Fig. 1 is a vertical longitudinal section of a bending machine, in which a horizontal work table supports a hot plate serving for rendering the wood pliable by dry heat.

Figs. 2 and 3 are a longitudinal section and partly an end view, respectively, drawn to a larger scale, of a device for fixing the work to the drum.

Figs. 4 and 5 are an axial section and an end view, respectively, of a drum.

Figs. 6 and 7 are a front view and an end view, re-

2

spectively, of the abutment member having the form of a roll and of means for varying its position relative to the drum.

Referring to the drawings and first to Fig. 1, 1 is the rear wall of a pair of parallelly spaced walls forming the machine bed. These walls are connected with each other by the work table 2 and by bracing members 3 and 4. A channel iron 5 is mounted on the inner side of each wall 1. From each wall 1 extends a rigid arm 6. Between the two arms is supported an axle 11, on which is pivoted a double-armed lever in the form of a girder 7 (or a pair of such girders) for rocking motion. On the rear arm of this girder an electro-motor 18 is mounted on a plate 19 supported by a horizontal arm 17 of a lever 9, the lower end of which embraces a pin 8 on a nut 14, which surrounds a screw spindle 15 supported in bearings 25. By rotating this spindle by means of the hand wheel 31, the lever can be moved and the girder 7 rocked about the axle 11 to lift or lower its free end, in which is supported the drum axle 16.

The girder and the weight of the drum 21 being counter-balanced either entirely or partly, by the weight of the motor 18, adjustment of the drum in the vertical direction is easy and the drum is locked in position by the arm 9 and nut 14.

A gear 20 driven by the motor and its speed reducer (not shown) drives the sprocket 13 and by means of a chain 12 the sprocket 23 keyed on a sleeve 26 (Fig. 4) which rides on the axle 16 and, by means of pins 49, grips one end wall 46 of the drum which can then be rotated directly by the motor 18.

The free end of the girder 7 can be fixed in its position relative to the work also by means of a threaded connecting rod 41 (Fig. 1) pivoted on an axle 42 supported in a bearing 43 on the front arm 6. The free end of the rod 41 can be introduced in a slot 71 in the free end of the axle 16 and a large nut 44 riding on the threaded rod will serve as a rest for the axle, which is supported at the end of the girder 7. The drum 21 shown in Figs. 4 and 5 is closed by two heads 46 and 47 formed with perforations 48. The sleeve 26 encircling one end of the axle and carrying the driven sprocket 23 carries pins 49, which, when the drum is slipped on the axle enters the perforations 48 of the drum head 46. Another sleeve 50 surrounding the free end of the axle 16 also carries pins 51 which enter the perforations 52 in the drum head 47. Both the sleeves 26 and 50 ride loosely on the axle 16.

The drum shell is heated by hot air. Resistance wires 53 extending between discs 54 mounted on the axle and fed with current by means of leads 55 entering the supported end of the axle and projecting radially through the perforation 56 of the axle wall provide the heat for heating up the air enclosed in the drum shell.

The clamping of the workpiece 40 (Figs. 2 and 3) to the drum 11 can be effected by hand with the aid of a device such as shown in Figs. 2 and 3. The heavy steel bar 57 of square cross-section is suspended for sliding motion by means of pins 58 in a rigid channel 59, to the end of which are hinged by their middle arms 60 hooks 61 of inverted F-section. The horizontal arms 62 of the hooks carry vertical screw bolts 63. The free ends of the hooks are gripped by the upturned ends 64 of a leaf spring 65, which is acted upon by a screw bolt 66 passing through a perforation in the middle section of the spring. The spring is forced downwardly by a flange 67 formed on the bolt 66, when this bolt is screwed down by means of the hand wheel 68. When the spring is flattened by the pressure exerted by the screw bolt 66, its ends in sliding on the channel 59 will move a short distance outwardly and will push the top

ends of the hooks 61 outwardly, whereupon the bottom ends are swung inwardly towards the drum heads, causing the bolts 63 to grip from below the ends of the drum shell 68. On the bolt 66 being screwed further down, it comes to rest on the bar 57 and raises the channel 59 until the bolts 63 have firmly gripped the cylinder shell and thereby clamped the workpiece between the bar and the shell of the drum. On the bolt 66 being loosened again the leaf spring will return to its original form and will become shorter, pulling the top ends of the hooks inside and the bottom ends of the hooks towards the outside, thus disengaging the device from the drum.

The bending roll 70 (Figs. 1, 6 and 7) which acts as an abutment met by the workpiece when this latter is pulled off the worktable and tries to rise is mounted in ball bearings (not shown) in the end walls 71 of a carriage 72 of channel section, open at the bottom. The end walls 71 carry on the outside lugs 73 extending at an angle to the carriage top and bottom edges. The lugs are arranged to slide in the inclined guide grooves 74 (Fig. 1) formed on the inner sides of the horizontal channels 5. A vertical lug 75 formed with a screw threaded perforation 76 is mounted on the carriage top. It rides on a threaded spindle 77 supported in inclined positions in bearings 78. By rotating the spindle with the aid of a crank handle 79 placed on its projecting end, the roll 70 can be shifted both relative to the drum 21 and to the work on the heater plate 37 which is supported by the worktable 2. By shifting the bending roll in this manner, not only the distance of the roll from the drum, but also the distance of the roll from the surface of the heater plate and work is increased or decreased, in accordance with the thickness of the work.

The heater plate 37 is heated by an electric current.

In order to exchange a drum for another one of smaller or larger diameter, the rod 41 is withdrawn from the slot 71 of the shaft 16 and pulled back by the counterweight, the right hand sleeve 50 is taken off, the drum is slid along the shaft and removed, the new drum slid on, until the pins 49 of the left hand sleeve have entered the perforations of the head 46 and the right hand sleeve put in place again with the pins 51 entering the perforations of the head 47.

The girder 7 is then adjusted by turning the screw spindle 15 by means of the wheel 31, until the drum contacts the work.

I wish it to be understood that I do not desire to be limited to the details disclosed in the foregoing specification and in the drawings for obvious modifications will occur to a person skilled in the art.

I claim:

1. In a wood-bending machine the combination, with a machine bed, of a drum shaft, a former-drum on said shaft and an abutment member positioned in opposed relation to the drum for cooperation with the drum to contact opposite sides of the work extending between them, a lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum.

2. In a wood-bending machine the combination, with a machine bed, of a drum shaft, a former-drum on said shaft and an abutment member positioned in opposed relation to the drum for cooperation with the drum to contact opposite sides of the work extending between them, a double-armed lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum.

3. In a wood-bending machine the combination, with a machine bed, of a drum shaft, a former-drum on said shaft and an abutment member positioned in opposed relation to the drum for cooperation with the drum to contact opposite sides of the work extending between them, a double-armed lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum mounted on the other end of said lever.

4. In a wood-bending machine the combination, with a machine bed, of a drum shaft, a former-drum on said shaft and an abutment member positioned in opposed relation to the drum for cooperation with the drum to contact opposite sides of the work extending between them, means on said machine bed for simultaneously adjusting said abutment member in horizontal and in vertical position, a lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum.

5. In a wood-bending machine the combination, with a machine bed, of a drum shaft, a former-drum on said shaft and an abutment member positioned in opposed relation to the drum for cooperation with the drum to contact opposite sides of the work extending between them, means on said machine bed for displacing said abutment member in a plane inclined at an acute angle relative to the plane of the drum shaft, a lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum.

6. In a wood-bending machine the combination, with a machine bed, of a drum shaft, a former-drum on said shaft and an abutment member positioned in opposed relation to the drum for cooperation with the drum to contact opposite sides of the work extending between them, a lever pivoted to said machine bed on a horizontal axis for rocking movement in a vertical plane and supporting, lifting and lowering said shaft, mounted at one end, in exactly horizontal position, means at the rear end of said lever for fixing said lever and shaft at any level determined by the drum radius and means for rotating said drum.

7. In a wood-bending machine the combination, with a machine bed, of a drum axle, two sleeves rotatable on said axle, a former-drum on said sleeves and an abutment member positioned in opposed relation to the drum for cooperation with the drum to contact opposite sides of the work extending between them, a lever pivoted to said machine bed on a horizontal axis for rocking movement in a vertical plane and supporting, lifting and lowering said axle, mounted at one end, in exactly horizontal position, means at the rear end of said lever for fixing said lever and axle at any level determined by the drum radius and means for rotating said drum.
